(57) **CLAIM**

The ornamental design for a charging device, as shown and described.

DESCRIPTION

FIG. 1 is a front, top perspective view of a charging device;

FIG. 2 is a top view thereof;

FIG. 3 is a bottom view thereof;

FIG. 4 is a front view thereof;

FIG. 5 is a rear view thereof;

FIG. 6 is a side view thereof as seen from the left-hand side of FIG. 5;

FIG. 7 is a side view thereof as seen from the right-hand side of FIG. 5;

FIG. 8 is a side view thereof as seen 60 degrees toward the left-hand side from FIG. 5; and,

FIG. 9 is a side view thereof as seen 60 degrees toward the right-hand side from FIG. 5.

The broken line showing of the ports is included for the purpose of illustrating environmental structure and forms no part of the claimed design.
